(57) **CLAIM**

The ornamental design for a railing bracket as shown and described.

DESCRIPTION

FIG. 1 is a front, right perspective view of a railing bracket showing our design according to a first embodiment; FIG. 2 is a front view thereof;

FIG. 3 is a back view thereof;

FIG. 4 is a left side view thereof;

FIG. 5 is a right view thereof;

FIG. 6 is a top view thereof; and,

FIG. 7 is a bottom view thereof.

The long-and-short broken lines form an unclaimed boundary, and form no part of the claim. The even-length broken lines form unclaimed portions of the railing bracket.
